US00D545812S

(12) **United States Design Patent** (10) **Patent No.:** **US D545,812 S**
Grady et al. (45) **Date of Patent:** **** Jul. 3, 2007**

(54) **MULTI-FUNCTION DOCKING ASSEMBLY
FOR PORTABLE DIGITAL MEDIA STORAGE
AND PLAYBACK DEVICE**

(75) Inventors: **Jeff Grady**, Charleston, SC (US);
Andrew Green, Mount Pleasant, SC (US); **Garey De Angelis**, Charleston, SC (US)

(73) Assignee: **Netalog, Inc.**, Durham, NC (US)

(**) Term: **14 Years**

(21) Appl. No.: **29/243,238**

(22) Filed: **Nov. 22, 2005**

(51) **LOC (8) Cl.** **14-02**

(52) **U.S. Cl.** **D14/217; D14/496; D3/318**

(58) **Field of Classification Search** **D14/496, D14/217, 224, 251, 260, 299, 483, 238; D3/215, D3/218; 455/73, 93, 99, 90.1–90.3, 345, 455/347, 575.1, 899, 575.8, 575.9, 575.2; 379/420, 449, 455, 446**

(57) **CLAIM**

The ornamental design for a multi-function docking assembly for portable digital media storage and playback device, as shown and described.

DESCRIPTION

FIG. 1 is a perspective view of a multi-function docking assembly for portable digital media storage and playback device showing our new design;

FIG. 2 is a right side elevation view thereof;

FIG. 3 is a front elevation view thereof;

FIG. 4 is a rear elevation view thereof;

FIG. 5 is a top plan view thereof; and,

FIG. 6 is a bottom plan view thereof.

The left side elevation view is a mirror image of the right side.

All structures indicated in broken lines are not part of the design sought to be patented.
